[57] CLAIM

The ornamental design for a tumbler or similar article,
as shown and described.

DESCRIPTION

FIG. 1 is a side elevational view of a tumbler or similar
article showing my new design, all sides being the same;

FIG. 2 is a bottom plan view thereof;

FIG. 3 is a vertical longitudinal sectional view thereof
taken along line 3—3 of FIG. 2, looking in the direction
of the arrows;

FIG. 4 is a top plan view thereof;

FIG. 5 is a side elevational view of a second form of a
tumbler or similar article showing my new design, all
sides being the same;

FIG. 6 is a bottom plan view of the second form;

FIG. 7 is a sectional view of the second form taken
along line 7—7 of FIG. 6, looking in the direction of the
arrows; and

FIG. 8 is a top plan view of the second form.

FIG. 1.

FIG. 3.

FIG. 2.

FIG. 4.

FIG. 5.

FIG. 7.

FIG. 6.

FIG. 8.
